REFRIGERATION APPARATUS

Graham S. McCloy, Springfield, Mass., assignor
to Westinghouse Electric & Manufacturing
Company, East Pittsburgh, Pa., a corporation
of Pennsylvania

Application July 10, 1941, Serial No. 401,691

4 Claims. (Cl. 62—103)

This invention relates to refrigeration apparatus and more especially to the disposition of condensate in a domestic refrigerator of the mechanical type as distinguished from the ice-cooled refrigerator.

The object of the invention is to provide a simple and inexpensive means for disposing of the condensate dripping from the cooling unit of a mechanical refrigerator.

Another object is to provide a readily cleanable passage through the refrigerated food-storage chamber of a refrigerator for the condensate dripping from the cooling unit.

A further object of the invention is to provide an open passage for the liquid condensate flowing through the food-storage chamber of a refrigerator, which passage is not readily obstructed by the comestibles in the food-storage chamber.

These and other objects are effected by my invention as will be apparent from the following description and claims taken in connection with the accompanying drawing, forming a part of this application, in which:

Fig. 1 is an elevation of a domestic refrigerator with a large portion thereof broken away to show the embodiment of the invention;

Fig. 2 is a section on the line II—II of Fig. 1; and

Fig. 3 is a section on the line III—III of Fig. 1.

Referring now to the drawing, the reference numeral 10 designates the outer shell of a refrigerator cabinet 11. A horizontal partition 12 divides the cabinet 11 into an upper compartment and a lower compartment 22. The upper compartment comprises an inner liner 13 spaced from the outer shell 10 and heat-insulating material 15 located between the inner liner and the outer shell 10. The front of the upper compartment is open to provide an access opening, and a heat-insulated door 16 supported on hinges 17 is provided for the opening. The inner liner 13 and the door 16 define a food-storage chamber 18, which chamber 18 is provided with shelves 19. An evaporator cooling unit 21 is located in the upper portion of the chamber 18 and is maintained at a temperature of approximately 20° F.

The lower compartment 22 contains the refrigerating machinery 23 which supplies the cooling unit 21 with a refrigerant liquid. The refrigerating apparatus 23 is of conventional design and will be described subsequently. The lower or machine compartment 22 comprises an air passage having an entrance opening 24 provided with a hinged grill 26 and an exit open-

ing 27 in the rear wall of the compartment 22. A flow of air is established through this passage by the heat of the refrigerating machinery 23 when in operation.

5 The cooling unit 21 accumulates a layer of frost thereon which must be periodically removed, preferably by rendering the refrigerating machinery 23 inactive so that the frost on the cooling unit 21 may melt and run off. A meat-storage receptacle 20 is supported immediately below the cooling unit on one of the shelves 19 and the cover of the meat-storage receptacle 20 is formed into a tray 28 supported underneath the cooling unit 21 on two rods 29 which comprise portions of a shelf structure not otherwise shown in the drawing. The tray 28 is provided with a short nozzle 31 adjacent the bottom wall thereof on which a short rubber tip 30 is secured. The tip 30 extends into a vertical groove 32 formed in the rear wall of the inner liner 13. The tip 30 preferably extends to the rear wall of the groove 32 so that the condensate flowing from the nozzle 31 runs down the rear wall of the groove 32.

10 The groove 32 extends downwardly to the lower wall 33 of the inner liner 13 and a discharge nipple 34 is formed in the lower wall 33 at the base of the groove 32. The discharge nipple 34 communicates with a tube 36 which may be connected 15 to any convenient means for the disposal of water such as a drain or, as shown in this embodiment of the invention, to an open trough 37 which conducts the condensate into a pan 38 located in the path of the air flowing through the lower compartment 22.

20 It will be apparent from the above that the condensate dripping from the cooling unit 21 will drop into the tray 28 and thereupon flow through the nozzle 31, down the rear wall of the groove 32 to the nipple 34, through the nipple 34, the tube 36, and the trough 37 to the pan 38. The groove 32 is relatively narrow so that comestibles placed on the shelves 19 are not readily pushed into the groove 32 and will, therefore, 25 not be wetted by the condensate running down the rear wall of the groove 32.

25 In the embodiment shown, the condensate conducted into the pan 38 will evaporate into the current of air flowing through the machine compartment 22. The groove 32 being open and the tray 28 being removable are readily cleaned. The pan 38 is also removable through the opening 24 for periodic removal of dust or food spillage. The pan 38 may be placed in heat exchange relationship with the casing 41 or with the con-

denser 43 if fast evaporation of the condensate in the pan 38 is desired, since both the casing 41 and the evaporator 43 are heated during the operation of the refrigerating machinery 23. An alternative location of the pan is shown by dotted lines at 39, which location eliminates the use of a trough.

The refrigerating machinery 23 in the lower compartment 22 and the remaining structure shown in Fig. 1 is of the compressor-condenser type and comprises a sealed casing in which a compressor and an electric motor for driving the same are housed. Refrigerant vapor is withdrawn through a tube 42 from the evaporator 21, is compressed by the compressor in the sealed casing 41, and passed through a tube 44 to the upper portion of a vertical U-shaped plate condenser 43. The vapor passes downwardly through a tube 45 forming a part of the condenser 43, is condensed in the tube 45, and then passes upwardly through a capillary impedance tube 46 to the evaporator 21, wherein it vaporizes and absorbs heat from the food-storage chamber 18. Both the casing 41 and the plate condenser 43 are heated during the operation of the compressor. The U-shaped plate condenser 43 forms an air duct 50, the lower end of which is closed by a plate 54. The duct 50 communicates with the opening 27 in the machine compartment 22 and acts as a chimney to draw air therethrough and over the pan 38.

The electric power for the refrigerating machinery 23 is supplied through an electrical conduit 47 which passes through a thermostatic switch (not shown) in a housing 48 and thereafter through conduit 49 to the sealed casing 41 and to the motor therein (not shown). The temperature-responsive switch (not shown) in the casing 48 is actuated by the pressure of a volatile fluid in a bulb 49. The pressure of the volatile fluid is transmitted to the thermostatic switch through a tube 51. The temperature at which the food-storage chamber 28 is maintained may be adjusted by turning a wheel 52 on a shaft 53, which shaft communicates with the thermostatic switch.

The above-described method of condensate disposal is adapted for use with a mechanical defrost clock which renders the refrigerating machinery inactive at intervals for defrosting the cooling unit 21, such as a clock which renders the refrigerating machinery 23 inactive during a short period each night.

It will be apparent from the above that this invention provides a simple and inexpensive means for the disposal of the condensate dripping from the cooling unit of a refrigerator and that it also provides a passage for the condensate through the refrigerated chamber, which passage is readily cleaned and which is not likely to be obstructed by comestibles placed in the refrigerator.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. Structure for removing condensate from a refrigerator having a food-storage chamber including a side wall, a cooling unit in the upper portion of said chamber, an open groove on the interior surface of said side wall extending downwardly from a point adjacent the cooling unit, means for conducting liquid condensate from said cooling unit to the groove at said point, and a drain communicating with the lower end of said groove, said groove extending in a substantially direct path along said side wall from said point to said drain, whereby condensate from said cooling unit flows downwardly in said groove to said drain.
- 5 2. Structure for removing condensate from a refrigerator having a food-storage chamber including a side wall, a cooling unit in the upper portion of said chamber, a storage receptacle immediately below the cooling unit and a cover for said receptacle, said structure comprising an open groove on the interior surface of said side wall extending downwardly from a point adjacent the cooling unit, means formed in said cover to conduct liquid condensate from said cooling unit to the groove at said point and a drain communicating with the lower end of said groove, said groove extending from said point to said drain, whereby condensate from said cooling unit flows downwardly in said groove to said drain.
- 10 3. Structure for removing condensate from a refrigerator having a storage compartment, a machine compartment below said storage compartment, and a cooling unit in the upper portion of said storage compartment, said structure comprising a drip collector for catching moisture dripping from said cooling unit, a substantially vertical groove in the side wall of said food-storage compartment, said groove being relatively narrow so that the possibility of entry of comestibles stored in said compartment into said groove is minimized, a drain for conducting the condensate in the drip collector to said groove, said machine compartment including a duct through which air passes, a pan in said duct, and an outlet in said storage compartment for conducting the condensate from said groove to said pan, the condensate evaporating into the air passing through said duct.
- 15 4. Structure for removing condensate from a refrigerator having a storage compartment, a machine compartment below said storage compartment, and a cooling unit in the upper portion of said storage compartment, said structure comprising a drip collector for catching moisture dripping from said cooling unit, a substantially vertical groove in the side wall of said food-storage compartment, said groove being relatively narrow so that the possibility of entry of comestibles stored in said compartment into said groove is minimized, a drain for conducting the condensate in the drip collector to the portion of the wall of said storage compartment forming the deepest portion of said groove, said machine compartment including a duct through which air passes, a pan in said duct, and an outlet in said storage compartment for conducting the condensate from said groove to said pan, the condensate evaporating into the air passing through said duct.
